UNITED STATES PATENT OFFICE.

CHARLES F. LINSLEY AND REUBEN F. CROOKE, OF MERIDEN, CONNECTICUT,
ASSIGNORS TO THE BRADLEY & HUBBARD MFG. CO., OF SAME PLACE.

DESIGN FOR A LAMP-BODY.

SPECIFICATION forming part of Design No. 29,223, dated August 16, 1898.

Application filed June 11, 1898. Serial No. 683,246. Term of patent 14 years.

To all whom it may concern:

Be it known that we, CHARLES F. LINSLEY and REUBEN F. CROOKE, of Meriden, in the county of New Haven and State of Connecticut, have invented a new Design for a Lamp-Body; and we do hereby declare the following, when taken in connection with the accompanying drawings and the letters of reference marked thereon, to be a full, clear, and exact description of the same, and which said drawings constitute part of this specification, and represent, in—

Figure 1, a view in elevation of a lamp-body embodying our newly-invented design; Fig. 2, a view in transverse section through the fount of the lamp-body on the line *a b* of Fig. 1; Fig. 3, a corresponding view of the foot of the lamp-body on the line *c d* of Fig. 1.

This invention relates to a design for a lamp-body; and the design consists in the configuration herein shown and described.

As herein shown, our newly-invented design comprises a lamp-fount *A*, a lamp-foot

B, and a lamp-body composed by joining the said fount and foot. The distinguishing feature of our design is common to the said lamp-fount and lamp-foot, and therefore to the said lamp-body, and consists of plain facets *C*.

We claim—

1. In a design for a lamp-body, the design for the lamp-fount as herein shown and described.

2. In a design for a lamp-body, the design for the lamp-foot, as herein shown and described.

3. The design for a lamp-body as herein shown and described.

In testimony whereof we have signed this specification in the presence of two subscribing witnesses.

CHAS. F. LINSLEY.
REUBEN F. CROOKE.
